UNITED STATES PATENT OFFICE

164,991

HEADADDRESS

Weldon Eli Hedley, San Pedro, Calif.

Application September 18, 1950, Serial No. 12,246

Term of patent 14 years

(Cl. D3—13)

To all whom it may concern:

Be it known that I, Weldon Eli Hedley, a citizen of the United States, residing at San Pedro, in the county of Los Angeles, State of California, have invented a new, original, and ornamental Design for Headdress, of which the following is a specification, reference being had to the accompanying drawing, forming part hereof.

The figure on the drawing is a perspective view of a headdress, showing my new design.

I claim:

The ornamental design for a headdress, substantially as shown.

WELDON ELI HEDLEY,
